UNITED STATES PATENT OFFICE.

HENRY D. JAMES, OF EDGEWOOD PARK, PENNSYLVANIA, ASSIGNOR TO WESTINGHOUSE ELECTRIC & MANUFACTURING COMPANY, A CORPORATION OF PENNSYLVANIA.

CONTROL SYSTEM.

1,392,057.

Specification of Letters Patent. Patented Sept. 27, 1921.

Application filed August 10, 1918. Serial No. 249,344.

To all whom it may concern:

Be it known that I, HENRY D. JAMES, a citizen of the United States, and a resident of Edgewood Park, in the county of Allegheny and State of Pennsylvania, have invented a new and useful Improvement in Control Systems, of which the following is a specification.

My invention relates to reversing systems for electric circuits, especially electric motors, and is particularly adapted for use in connection with motor-control systems of the character set forth in my copending application, Serial No. 236,937, filed May 27, 1918, control systems.

The dominant feature of the systems of my said application is that a coil designed to actuate the relays for controlling the contactors which short-circuit the accelerating resistor is shunt-connected across the terminals thereof. The relays may be of the type illustrated in a copending application by De Camp, Serial No. 241,259, filed June 21, 1918, and assigned to the Westinghouse Electric & Manufacturing Co., or they may be of any ordinary type. In the latter event, a separate actuating coil may be employed for each relay, all the coils being connected in multiple with the resistor.

As explained in my above-mentioned application, means must be provided, owing to the very nature of the system, for insuring that the motor, when restarted after a brief interval following its disconnection from the line, shall not be reconnected to the line with the accelerating resistor short-circuited. Several such means are illustrated in my above application. This precaution is of particular value when the motor, while running at full speed in one direction, is reversed so as to operate at full speed in the opposite direction.

An object of my invention is to provide a safe starting system for a motor so controlled.

Another object of my invention is to provide a reversing system for a motor governed by such a controlling system.

Other objects of my invention will be made clear hereinafter.

If relays be employed of the type described in the aforementioned application by De Camp, in which a main armature controls the closing of the relays, I may so arrange the control circuits that it will be impossible

to start or reverse the motor unless the main armature occupies its normal, inoperative position. This insures that the relays are open, and that the accelerating resistor is, therefore, in the circuit of the motor, before the motor is started. I may effect this object electrically or mechanically.

If the mechanical method be employed, the main armature may be so designed as to be actuated to its normal position, upon the reversal of the motor, by a projection carried by a bar connecting the reversing contactors. If the electrical method be adopted, the main armature may, itself, be a contact-bearing member, the contact members of which may initially close the motor circuit when the armature member occupies its normal, inoperative position, after which the contact members may be short-circuited so as not to break the starting circuit upon the actuation of this armature member to its operative position.

I have herein illustrated several systems embodying this principle. The circuits may be so arranged as to prevent the reversal of the motor until after a time interval has elapsed, caused by the reversal of the magnetism of the coil for controlling the relays. I have also illustrated one method of reversing a motor the acceleration of which is effected by the use of ordinary relays having individual actuating coils.

My invention will be understood by reference to the accompanying drawings, in which Figures 1, 2 and 3 are, respectively, a side and an end elevation and a plan view of a relay of the type illustrated in the aforementioned application by De Camp. Fig. 4 is a detail of a modification of this relay. Fig. 5 is a diagrammatic view of circuits and apparatus illustrating one form of my invention as applied to an accelerating system employing a relay of the type shown in Figs. 1 to 3. Figs. 6 and 7 are similar views of modifications. Fig. 8 is a modified system employing a relay, a detail of which is illustrated in Fig. 4. Fig. 9 is a reversing system, arranged according to my invention, employing ordinary relays.

As my invention is of particular value in connection with a system employing the De Camp relay above referred to, and illustrated in Figs. 1 to 4, it will conduce to clearness to describe this relay first.

An insulating panel 29 carries two brack-

ets 30 and 31 supporting the coils 22 and 23 which, when energized by current flowing through them, create magnetic fields for attracting an armature 32 and armatures 33, 34 and 35. A compression spring 36 is adjustably mounted upon a non-magnetizable rod 37 that is slidably mounted in projections 38 and 39 which are integral with a member 31. The projection 38 serves also 10 as a pole piece for the armature 32 and the projection 39 as a pole piece for the armatures 33, 34 and 35. A bar 40 is rigidly connected to the rod 37 and normally engages the armatures 33, 34 and 35. The 15 spring 36 thus normally maintains the armatures 33, 34 and 35 in their open positions, with the members 41, which are carried by these armatures, in contact with the pole piece 39. The members 41 are prefer- 20 ably of non-magnetizable material to prevent "freezing."

The armature 32 is provided with brackets 42, which are pivotally mounted upon the bracket 30, and is normally maintained 25 in contact with the lower end of the rod 37 by a relatively weak spring 43. The bracket 30 supports a non-magnetizable U-shaped member 44 between the arms of which are pivotally mounted the armatures 33, 34 and 35, which carry, respectively, the movable 30 contact members 45, 46 and 47 of the relays 25, 26 and 27. The corresponding stationary contact members 48, 49 and 50 are mounted upon the insulating panel 29.

35 Springs 51 are attached to longitudinally adjustable members 52 and to the other ends of the members 41. The pole piece 39 is provided with longitudinally adjustable members 53 to regulate air gaps 70 between 40 these members and the corresponding armatures. By means of this adjustment, or by means of the members 52, which control the tension of the springs 51, the action of the magnetic flux produced by the coils 22 and 45 33, 34 and 35 may be so regulated that the armatures 33, 34 and 35 will be operated in proper sequence.

The armature 32 is provided with an extension 54 of insulating material which carries 50 a switch member 55 for coöperating with stationary switch members 56 mounted upon the insulating panel 29. As shown in Fig. 1, the switch members 55 and 56 are closed when the armature 32 occupies its 55 open position. If desired, the switch member 56 may be replaced by a switch member 57, Fig. 4, so that contact between the switch members 57 and 55 will be made when the armature 32 occupies its closed position.

60 The operation may be briefly described as follows: Upon current flowing through the coil 22, a magnetic field is created which causes the armature 32 to be attracted toward the pole piece 38. The force of the 65 spring 36 is thereupon overcome, and the

bar 40 is moved out of engagement with the armatures 33, 34 and 35, the stop members 41 of which are, nevertheless, maintained in engagement with the pole piece 39 until the flux of the magnetic field becomes successively sufficiently low to permit the springs 51 to successively actuate the movable contact members 45, 46 and 47, thereby to close the relays 25, 26 and 27. In the event that the magnetic field becomes too weak to hold 75 the armature 32 in its elevated position, the spring 36, becoming released, will separate the movable from the stationary contact members. Actuation of the armature 32, of course, effects corresponding actuation of the 80 switch member 55.

I shall now describe the invention illustrated in Fig. 5. A motor, the armature of which is shown at 1 and the shunt field-magnet winding at 2, is connected between 85 line conductors 3 and 4, with a regulating resistor 6 normally in series with the armature 1. A plurality of reversing contactors 58, 59, 60 and 61 control the direction of rotation of the motor. A master controller 90 or switch 7 controls the actuation of the reversing contactors through the medium of energizing coils 62, 63, 64 and 65, which are connected in circuits including the contact members 55 and 56. 95

The movable contact members of contactors 66 and 67 are, respectively, mechanically interlocked with the movable contact members of the reversing contactors 58 and 59 to provide shunt circuits for the contact 100 members 55 and 56. The master controller 7 is designed to close contact members 9 and 18. One or more contactors 10, 11 and 12 (three are illustrated) control the shunting of successive portions 13, 14 and 15 of the 105 regulating resistor 6 through the medium of energizing coils 19, 20 and 21. The coil 22 is connected across the terminals of the resistor 6 at 79 and 80. The energizing of the coil 22 causes the successive closing of the 110 relays 25, 26 and 27, as above described, in accordance with the strength of the current 115 passing through the coil 22.

The coil 19 is connected in a circuit leading from the line conductor 3, by the conductor 28^a, through the reversing contactor 59, (assuming this contactor and the contactor 60 to be closed) the armature 33 and the relay 25 to the point 79 and from that point, through the reversing contactor 60 120 to the line conductor 4. If the reversing contactors 58 and 61 are closed instead, the current through the coil 19 is in the reverse direction. The coils 20 and 21 are similarly connected to the relays 26 and 27. The coil 125 23 is connected, by conductor 28, in parallel with the coil 21 and in series with a high resistance 24, so that the current in the coil 23, like that in the coils 19, 20 and 21, is reversed when the motor is reversed. 130

Upon moving the controller 7 to the left, a circuit is established from the line conductor 3 through the controller arm 7, which is electrically connected thereto, the contact member 9, the coils 63 and 64 in parallel, one of the contact members 56, the contact member 55 and the other contact member 56 to the line conductor 4. The coils 63 and 64 are thereupon energized to cause the closing of the reversing contactors 59 and 60. A circuit is now established extending from the line conductor 3, by the conductor 28^a, through the reversing contactor 59, the motor armature 1, the resistor 6, the point 79 and the reversing contactor 60, to the line conductor 4. A shunt circuit is established through the field-magnet winding 2 when the main-line switch (not shown) is closed. A circuit is also established through the coil 22 in parallel relation to the resistor 6, the coil 22 and the resistor 6 being connected at points 80 and 79.

The energizing of the coil 22 creates a magnetic field which attracts the armature 32 to the pole piece 38 and instantly separates the contact members 55 and 56. This separation breaks the circuit, above described, of the coils 63 and 64. Holding circuits for these coils have previously been established, however, by the contactor 67, mechanically interlocked with the reversing contactor 59. The rod 37 is actuated by the armature 32, in opposition to the force of the spring 36, to force the bar 40 away from the armatures 33, 34 and 35.

If the current is above a previously-selected safe value, the flux of the magnetic field created by the coil 22 will overcome the forces of the springs 51, and the armatures 33, 34 and 35 will remain with the stops 41 in engagement with the pole piece 39 (Fig. 1). As the motor accelerates and the current decreases in value the magnetic flux set up by the coil 22 diminishes.

When the flux has decreased to a predetermined value, the spring 51 attached to the armature 33 will overcome the force exerted by the flux of this field so that the relay 25, controlled by the armature 33, will be closed. The time when this operation will occur will depend upon the width of the air gap 70 and the tension of the spring 51. The armatures 34 and 35, however, will remain open. The closing of the relay 25 establishes a circuit which extends from the line conductor 3, by the conductor 28^a, through the reversing contactor 59, the armature 33, the contact members 45 and 48 of the relay 25, and the actuating coil 19 to the point 79 and from there, through the reversing contactor 60, to the line conductor 4.

The coil 19 becoming energized, the contactor 10 becomes closed to short-circuit the

portion 13 of the resistor 6. The motor then further accelerates, and, by decreasing the voltage across the terminals of the coil 22, the magnetic field in the neighborhood of this coil is further weakened which permits the closing of the second relay 26 controlled by the armature 34. A circuit is then made from the line conductor 3, by the conductor 28^a, through the reversing contactor 59, the armature 34, the contact members 46 and 49, the coil 20 and the reversing contactor 60 to the line conductor 4. The coil 20, thus becoming energized, causes the closing of the contactor 11 and the consequent shunting of a second portion 14 of 80 the resistor 6.

After the motor has accelerated further, the magnetic field surrounding the coil 22 is again weakened and the relay 27 is closed, creating a circuit extending from the line conductor 3, by the conductor 28^a, through the reversing contactor 59, the armature 35, the contact members 47 and 50, the coil 21 and the reversing contactor 60 to the line conductor 4, thereby causing the closing of 90 the contactor 12 and the shunting of the third portion 15 of the resistor 6. The whole resistor 6 is then entirely shunted from the armature circuit and the armature 1 is connected directly across the line.

The shunting of the resistor 6 deenergizes the coil 22 which would release the armature 32 and cause the relays 25, 26 and 27 to be re-opened, thus resulting in deenergization of the coils 19, 20 and 21 and the 100 consequent re-insertion of the resistor 6 into the armature circuit, except for the coil 23, which becomes energized at the same time with the coil 21 upon the closing of the armature 35 of the relay 27. The coil 23 105 is connected in a circuit extending from the line conductor 3, by the conductor 28^a, through the reversing contactor 59, the armature 35, the contact members 47 and 50, the conductor 28, the coil 23, the resistor 24, the point 79 and the reversing contactor 60 to the line conductor 4.

The motor may be stopped by moving the controller arm 7 to the "off" position illustrated, thereby deenergizing the actuating coils of the reversing contactors and the consequent opening of the reversing contactors. The coil 23 is, thereupon, deenergized (which thereupon permits the opening of the relays 25, 26 and 27), as are also the 115 actuating coils 19, 20 and 21 of the contactors 10, 11 and 12. The motor may then be restarted, either in the same or in the reverse direction, by suitably manipulating the controller arm 7.

If, the motor remaining at high speed, the controller 7 be actuated to the "off" position, as illustrated, deenergizing the actuating coils of the reversing contactors and of the contactors 10, 11 and 12, these con- 130

tactors will fly open. Upon reclosing the controller arm 7, within a limited time thereafter, while the armature 1 is still rotating, the coil 22 is again energized, above the predetermined degree at which the relays 25, 26 and 27 are permitted to close and cause the reclosing of the contactors 10, 11 and 12 to short-circuit prematurely the entire resistor 6. This tends to have the effect of suddenly throwing the armature 1 into the line circuit without any resistance in series with it. In my copending application above mentioned, as also in Figs. 6 and 7 of the present application, are illustrated several methods for preventing this happening. The present application is more concerned with the preventing of similar occurrences upon the reversal of the motor from full speed in one direction to full speed in the opposite direction.

Assuming that the motor is operating at full speed and that it is desired to reverse it, the controller arm 7 is moved from, let us say, the extreme left-hand position to the extreme right-hand position of Fig. 5. The circuits of the motor are thereupon opened, as explained above, and a new circuit is established from the line conductor 3 through the controller arm 7, the contact member 18, the actuating coil 62 of the reversing contactor 58 and the actuating coil 65 of the reversing contactor 61 in parallel, and the contact members 55 and 56, if closed, to the line conductor 4.

The contact members 55 and 56, however, will not be closed until the coils 22 and 23 are sufficiently deenergized. The residual magnetism of one or both of these coils may maintain the armature 32 open, and the relays 25, 26 and 27 may, therefore, remain closed for a limited period of time. Upon the closing of the contact members 55 and 56 and the establishment of the above-traced circuit, a circuit is established for the motor which extends from the line conductor 3, by the conductor 28^b, the reversing contactor 61, the resistor 6, the armature 1 and the reversing contactor 58, to the line conductor 4, the circuit being, in this case, in a direction reverse to that described above. The coil 22 is energized in the same manner as above described, but the connections of its terminals are reversed, to cause the closing of the armature 32 and the consequent release by the bar 40 of the armatures 33, 34 and 35. The motor is now started in the opposite direction, but with the whole resistor in series with the armature. The relays will not close simultaneously, as might happen, in the absence of special provision thereagainst, if the motor were restarted in the same direction by reason of the reversal of polarity of the coil 22. The decreasing current in the coil 22 will, as before, cause the closing of the

armatures 33, 34 and 35 to cause the closing of the contactors 10, 11 and 12 to short circuit the resistor 6.

It will thus be seen that, with the system of Fig. 5, the purpose of my invention, namely, to prevent a reversal of the motor with the resistor short-circuited from the armature circuit, is accomplished in several ways. The circuits are so arranged that it is impossible, owing to the contact members 55 and 56, to effect the closing of either pair of the reversing switches until the energization of the coil 22 has decreased to a predetermined degree. Provision is made, also, for reversing the magnetic fields of the coils 22, 23, 19, 20 and 21 when the motor circuit is completed for operation in the opposite direction.

Another method of effecting this result is illustrated in Fig. 6. The coils 19, 20 and 21 are here directly controlled by the controller 7, through contact members 16 and 17, instead of through the reversing contactors. The coil 19 is connected in circuit as above described. The circuit of the coil 20, however, extends from the line conductor 3 through the controller arm 7, the contact member 16 or 17, the armature 34 and the relay 26, to the connecting point 68 of the resistors 13 and 14. When the resistor 13 is included in the circuit of this coil 20, the voltage is not sufficient to energize the coil 20, and the contactor 11, therefore, remains open. When the contactor 10 is closed, the circuit is completed to the line conductor 4 through this contactor, and the coil 20 becomes sufficiently energized to close the contactor 11. Similarly, the coil 21 is connected at 69 in a circuit which includes the relay 27 and the resistors 13 and 14, except when the contactor 11 is closed, thereby delaying the closing of the contactor 12 until the contactor 11 is closed.

A line contactor 5 is employed in addition to the reversing contactors 58, 59, 60 and 61, the coil 8 of which is in parallel circuit with the coils 19, 20 and 21. The reversing contactors 61 and 60, like the contactors 66 and 67, are here shown mechanically interlocked with the reversing contactors 58 and 59, respectively, though separate reversing contactors may, if desired, be employed, as in Fig. 5. The coils 22 and 23 are here shown as continuous, though this is merely a detail.

The operation is as follows: Upon actuating the controller arm 7 to the left, a circuit is established which extends from the line conductor 3, through the controller arm 7, the actuating coil 63 of the reversing contactors 59 and 60 and the contact members 55 and 56 to the line conductor 4. The reversing contactors 59 and 60 are thereupon closed to establish the motor circuit, which extends from the line conductor 3, by the

conductor 28^a, through the reversing contactor 59, the armature 1 and the reversing contactor 60 to the point 80 and from there, through the resistor 6 and the line contactor 5 to the line conductor 4.

The line contactor 5 is closed because of the energizing of the circuit including the coil 8 and the contact member 16. As above described, the coil 22, which is connected in

- 10 parallel with the resistor 6, will cause the closing of the armature 32 and later, the successive closing of the armatures 33, 34 and 35. The closing of the armature 32 separates the contact members 55 and 56, but a holding circuit for the coil 63 is previously closed at 15 67. This circuit extends from the line conductor 3, through the controller arm 7, the contact member 9, the coil 63, and the contactor 67 to the line conductor 4.
- 20 The closing of the armature 33 establishes a circuit which extends from the line conductor 3, through the controller arm 7, the contact member 16, the armature 33, the contact members 45 and 48 of the relay 25, the 25 coil 19, the point 79 and the line contactor 5, to the line conductor 4, whereupon the line contactor 10 closes to short-circuit the portion 13 of the resistor 6. The motor circuit now extends through the reversing contactors 30 and the armature 1, as above described, through the portions 15 and 14 of the resistor 6, to the point 68, and from there, through the contactor 10, to the point 79, and from there, through the line contactor 5, to 35 the line conductor 4.

Upon the closing of the armature 34, due to the decreasing magnetism of the coil 22, a circuit is established which extends from the line conductor 3, through the controller arm 7, the contact member 16, the armature 34, the relay 26 and the coil 20, to the point 68 and from there, through the resistor 13 and the contactor 5 to the line conductor 4. As stated above, the voltage of this circuit is not sufficient to cause the closing of the contactor 11. If, however, the contactor 10 is closed, then the above-described circuit continues from the point 68, through the contactor 10 to the point 79 and through the line contactor 5 to the line conductor 4, whereupon the contactor 11 becomes closed to short-circuit the resistor 14.

Similarly, the closing of the relay 27 will cause the energization of the coil 21 to cause 55 the closing of the contactor 12, and the consequent short-circuiting of the resistor 15. The armature circuit will then extend from the line conductor 3 by the line conductor 28^a, through the reversing contactor 59, the 60 armature 1, the reversing contactor 60, the contactor 12, the point 79 and the contactor 5, to the line conductor 4.

The closing of the relay 27 establishes not only the circuit of the coil 21 but also that 65 of the coil 23. This latter circuit extends

from the line conductor 3, through the controller arm 7, the contact member 16, the armature 35, the relay 27, the conductor 28, the resistor 24 and the coil 23, to the point 79, and thence, through the line contactor 5, to the line conductor 4. The coil 23 thus takes up the work of the coil 22 upon the short-circuiting of the latter coil coincident with the short-circuiting of the resistor 6.

If it is desired to reverse the motor, the 75 arm 7 is actuated to the right to make contact with the contact members 17 and 18. The circuit of the coil 8 is broken at the contact member 16 but is immediately re-established at the contact member 17. The actuating coil 63 becomes deenergized, but the coil 62 becomes energized, due to the closing of a circuit extending from the line conductor 3, through the controller arm 7, the contact member 18, the coil 62 and the contact members 55 and 56, if closed, to the line conductor 4. The switch members 55 and 56, however, will remain open until the magnetism of the coil 23 has sufficiently diminished to permit the armature 32 to be opened 90 by the spring 36 (Fig. 1). The relays 25, 26 and 27 will also be opened by this spring. The coil 22 becomes reenergized as soon as the motor circuit is closed. This circuit extends from the line conductor 3, through the 95 conductors 28^a and 28^b, the reversing contactor 61, if closed, the armature 1, the reversing contactor 58, the resistor 6, and the line contactor 5, to the line conductor 4. The connections of the coils 22 and 23 are 100 not reversed as in the system of Fig. 5 and there is not, therefore, the protecting feature of time lag by reason of the reversal of the corresponding magnetic fields. The protection of the motor is afforded by the fact 105 that, in the event that the coil 22 is sufficiently energized to cause the premature closing of the armatures 33, 34 and 35, the contactors 10, 11 and 12 will not close simultaneously, even though the circuits of the 110 coils 19, 20 and 21 be simultaneously closed by the closing of the relays 25, 26 and 27. The coil 20 cannot become sufficiently energized to cause the closing of the contactor 11 until the contactor 10 has closed and not 115 until the contactor 11 closes can the coil 21 cause the closing of the contactor 12.

The systems of Figs. 5 and 6 have the feature in common that it is impossible to restart or reverse the motor until the armature 32 occupies its normal position and this it can do only when the coil 22 or 23 is sufficiently deenergized. The systems of these two figures depend upon preventing a closing of the reversing contactors through the 120 medium of contact members controlled by the armature 32. In other words, the armature 32 controls an electrical interlock for the reversing switches. It is possible, however, to devise a system in which this inter- 125 130

lock shall be mechanical. Such a system I have shown in Fig. 7.

The reversing contactors 58 and 59 of this figure are mechanically interlocked in a well known manner by a bar 72, pivoted at 73, and the ends of which are pivotally connected to the reversing contactors. The bar is provided with a central projection 74 adapted to engage a spring-pressed rod 75, 10 slidably mounted in brackets 76 and 77 and the end of which is adapted to engage a projection 78 rigidly secured to the armature 32. The parts are so arranged that, upon the actuation of the reversing contactors from 15 one position to another, the projection 74 will engage the rod 75 to force it downwardly into contact with the projection 78 and thereby cause the opening of the armature 32.

20 This action releases the spring 36, (Fig. 1) whereupon the bar 40 causes the opening of the armatures 33, 34 and 35. The coils 19, 20 and 21, are deenergized which insures that the whole resistor will be in circuit with the armature before the motor is reversed. A drum controller 7 has been illustrated in this figure, though the controller of Figs. 5 and 6 may be employed and, conversely, the controller of this figure may be employed in the systems of Figs. 5 and 6. In this connection, it may be stated that, if the reversing contactors of Fig. 5 were mechanically interlocked with the armature 32, it would be possible to do away 35 with the necessity of employing the contact members 55 and 56 and the interlock contactors 66 and 67.

The operation of this system is as follows:

Upon the actuation of the controller to the 40 left to position *a*, a circuit is established which extends from the line conductor 3, through the actuating coil 63, the contact member 9 and the controller 7 to the line conductor 4. The coil 63 is accordingly energized to cause the closing of the reversing contactors 59 and 60. A circuit is then established which extends from the line conductor 3, by the conductor 28^a, through the reversing contactor 59, the armature 1, the reversing contactor 60, and the resistor 6 to the line conductor 4.

The bar 72 is, at the same time, actuated by the coil 63 about its pivot 73 to remove the projection 74 from engagement with the rod 75 to free the armature 32 which will be closed by the coil 22, the terminals of which are connected across the resistor 6 at the points 79 and 80. When the controller is actuated to the position *b*, a circuit is established which extends from the line conductor 3, through the armature 33, the contact members 45 and 48 of the relay 25, the actuating coil 19 and the contact member 16 to the line conductor 4, assuming, of course, 6 that the armature 32 has been actuated to its

closed position by the coil 22 and the armature 33 by the spring 51 (Fig. 1).

In similar fashion, the coils 20 and 21 are later closed at the proper time according to the degree of energization of the coil 22, 70 each of the coils 19, 20 and 21 causing the closing of the contactors 10, 11 and 12, respectively, to short-circuit the portions 13, 14 and 15 of the resistor 6. Upon the short-circuiting of the whole resistor, the coil 22 75 is, of course, short-circuited, but the coil 23 is now energized by the counter-electromotive force of the armature 1, since it is connected in a circuit extending from line conductor 3, through the conductor 28 and the resistor 24, to the point 80.

The coil 23 may be energized by line voltage, as in Figs. 5 and 6, or the systems of these two figures may be so arranged that the coil 23 of these figures will be energized 85 by the counter-electromotive force of the motor. The armature 32 will thus be maintained in closed position and the relays 25, 26 and 27 will remain closed to maintain the resistor 6 short-circuited. The controller 7, 90 of course, may be actuated step-by-step or to the position *d* in one step.

To reverse the motor, the controller 7 is moved in the opposite direction, either step-by-step or to the position *d* in one step, 95 whereupon the coil 62 will be energized to cause the closing of the reversing contactors 58 and 61. The coil 63 becoming deenergized, the bar 72, actuated by the coil 62, will cause the positive opening of the reversing switch 59 in opposition to the force of the spring-pressed bar 75 and it will furthermore actuate this spring-pressed bar to cause the opening of the armature 32 and, therefore, the opening of the relays 25, 105 26 and 27. This action will have the effect of re-inserting the resistor 6 into the armature circuit, which now extends from the line conductor 3, by the conductor 28^b, through the reversing contactor 61, the 110 armature 1, the reversing contactor 58 and the resistor 6 to the line conductor 4.

The motor will now be operated in the opposite direction. The coil 22, however, will be energized in the same direction and, 115 if the reversal take place within a sufficiently limited period of time, the coil 22 will be sufficiently energized to cause the premature closing of the relays 25, 26 and 27. This may be prevented, however, by either 120 the electrical interlocking feature illustrated in Fig. 6, consisting of tapping the circuits of the coils 20 and 21 at 68 and 69 or by a mechanical interlocking device diagrammatically illustrated in Fig. 7 at 81 125 and 82.

The mechanical interlocking device comprises so arranging the relays and contactors that, when the contactor 10 is open, the relay 26 will be open and, when the con- 130

tactor 11 is open, the relay 27 will be open. This insures that the contactors 10, 11 and 12 will not close simultaneously. The relay 25 may close to cause the closing of the 5 contactor 10 but not until the contactor 10 is closed can the relay 26 close to cause the closing of the contactor 11. Similarly, not until the contactor 11 has closed can the relay 27 be closed to cause the closing of the 10 contactor 12.

It is essential that, in the systems of Figs. 5 and 6, the circuits of the reversing contactors be closed in the open position of the armature 32. In Fig. 8, I have illustrated a system in which the reversing contactors are closed when the armature 32 occupies its closed position. In the system of this figure the relay is employed, a detail of which is shown in Fig. 4, the contact 15 members 55 and 57 being open when the armature 32 is open and closed when the armature 32 is closed.

A pair of reversing contactors, of the type illustrated in Figs. 6 and 7, are employed. They are shown interlocked by a bar 72, as in Fig. 7, though this bar is not absolutely essential. A similar bar is preferably employed also in the systems of the other figures. If desired, such a bar may be employed in connection with the systems of 20 Figs. 5 and 6. The controller 7 is here shown as comprising three contact members, insulated from each other, adapted to cooperate with stationary contact members on 25 each side thereof for direct and reverse operation, respectively. Two of the contact members are designed to close before the third, although the controller may be so operated as to close all of the contact members 30 together. The controller is preferably of the drum type, as in Fig. 7, but any other type of controller may be employed if desired. The motor shown in this figure is of the series-field type, but it may be of the 35 shunt-field or compound type. The motors of the systems of the other figures may also be either series or compound.

A line contactor 5 is employed in addition to the reversing contactors, as in Fig. 6, the 40 actuating coil 8 of this contactor being controlled by the contact members 55 and 57. A contactor 83 is mechanically interlocked with the contactor 5 for a purpose later described.

Assuming that the controller 7 has been moved one step to the left, a circuit is completed which extends from the line conductor 3 through the contact member 9^a, the actuating coil 63 and the series field-magnet winding 84 to the line conductor 4. The reversing contactors 59 and 60 are thereupon closed, whereupon a circuit is established from the line conductor 3, through the reversing contactor 59, the contact member 9^b, the coil 23, the resistor 24, the contactor 83,

the conductor 85, the conductor 71, the reversing contactor 60 and the series field-magnet winding 84, to the line conductor 4.

The armature 32 is thereupon closed, which closes the contact members 55 and 57, 70 whereupon a circuit is established from the line conductor 3, through the reversing contactor 59, the contact member 9^b, the actuating coil 8, the contact members 57 and 55, the conductor 71, the reversing contactor 75 60 and the series field-magnet winding 84, to the line conductor 4. The line contactor 5 is thereupon closed to establish the motor circuit which extends from the line conductor 3, through the reversing contactor 80 59, the armature 1, the line contactor 5, the resistor 6, the reversing contactor 60 and the field-magnet winding 84 to the line conductor 4.

The closing of the contactor 5 causes the 85 opening of the contactor 83, which de-energizes the coil 23. A circuit is, at the same time, established across the terminals of the resistor 6 for the coil 22, which extends from the point 80 to the point 79. The 90 armature 32 is thus initially closed independently of the coil 22. On the other hand, the coil 23 is energized but a brief period, so as not to serve to maintain the relays 25, 26 and 27 open. The coil 22, however, will 95 cause them to close in the manner previously described.

Upon the closing of the relay 25, assuming that the controller 7 has been actuated to its final position, a circuit is established which 100 extends from the line conductor 3, through the reversing contactor 59, the contact member 16, the actuating coil 19, the contact members 48 and 45, the armature 33, the conductor 71, the reversing contactor 60 and 105 the series field-magnet winding 84, to the conductor 4. This causes the closing of the contactor 10 and the consequent short-circuiting of the resistor 13. Similarly, the closing of the relay 26 causes the closing of 110 the contactor 11 to short-circuit the resistor 14, and the closing of the relay 27 causes the closing of the contactor 12 to short-circuit the resistor 15. The closing of the relay 27 establishes also the following circuit: from 115 the line conductor 3, through the reversing contactor 59, the contact member 9^b, the coil 23, the resistor 86, the relay 27, the armature 35, the conductor 71, the reversing contactor 60 and the field-magnet winding 84, to the 120 conductor 4. The circuit of the coil 23 is thus re-established to maintain the relays closed, though the coil 22 is de-energized upon the short-circuiting of the resistor 6. The motor is now connected directly across 125 the line conductors 3 and 4.

To reverse the motor, the controller 7 is moved in the opposite direction. The circuits above described are thereupon broken at the contact members 9^a, 9^b and 16, and 130

new circuits are made at the contact members 18^a, 18^b and 17. A circuit is first established which extends from the line conductor 3, through the contact member 18^a, the actuating coil 62, and the series field-magnet winding 84 to the line conductor 4, whereupon the reversing contactors 58 and 61 are closed to partly close a circuit extending from the line conductor 3 through the reversing contactor 61 to the point 79, thence through the resistor 6, the line contactor 5, which is open, the armature 1, the reversing contactor 58 and the field-magnet winding 84 to the line conductor 4.

15 A circuit is established from the line conductor 3, through the reversing contactor 61, the conductors 71 and 85, the contactor 83, the resistor 24, the coil 23, the contact member 18^b, the reversing contactor 58 and the field-magnet winding 84, to the line conductor 4. The coil 23 will thereupon be energized by a current in a direction opposed to that flowing when the motor was operating in the other direction. The armature 32, 20 therefore, will not be actuated until it is first returned by the spring 36 (Fig. 1) to its open position, when the magnetism produced by the newly created current in the coil 23 overpowers the residual magnetism 25 of the coil 22.

The armature 32 will then be reactuated to closed position when the current in the coil 23 builds up to a larger value. As soon as the armature 32 has been returned to its 30 normal position, a circuit is established extending from the line conductor 3, through the reversing contactor 61, the conductor 71, the contact members 55 and 57, the actuating coil 8, the contact member 18^b, the reversing contactor 58 and the field-magnet winding 84 to the line conductor 4, causing the opening of the contactor 83 and the closing of the contactor 5 to establish the motor circuit above described. Current now traverses the 45 motor circuit in the opposite direction.

The establishing of the motor circuit, of course, causes the reversal of current in the coil 22, so that any residual magnetism must first be overcome before the coil 22, which 50 now performs the function of the coil 23, the circuit of which was broken at the contactor 83, can be sufficiently energized to actuate the armatures 32, 33, 34 and 35, thus providing for the lapse of a sufficient time 55 interval to prevent the motor being restarted without the resistance in circuit with the armature. As in the system of Fig. 5, the circuits of the actuating coils 19, 20 and 21 will also be found to be traversed by current 60 flowing in a direction opposed to that flowing when the motor was operating in the reverse direction.

The circuit of the actuating coil 19, for example, extends from the line conductor 3,

through the reversing contactor 61, the conductor 71, the armature 33, the relay 25, the coil 19, the contact member 17, the reversing contactor 58 and the field-magnet winding 84, to the line conductor 4. A certain time interval will elapse before the current in this circuit will energize the coil 19 sufficiently to overcome the residual magnetism of this coil, during which interval of time the contactor 10 must be open. It will later close to short-circuit the resistor 13. Similarly, 75 the contactors 11 and 12 will later be closed to short-circuit the resistors 14 and 15.

The closing of the contactor 12 is effected by the closing of the circuit extending from the line conductor 3, through the reversing contactor 61, the conductor 71, the armature 35, the relay 27, the actuating coil 21, the contact member 17, the reversing contactor 58 and the field-magnet winding 84, to the line conductor 4. A branch circuit is, at the 80 same time, established from the relay 27, through the resistor 86, the coil 23, the contact member 18^b, the reversing contactor 58 and the field-magnet winding 84, to the line conductor 4 to reestablish the circuit of the 85 coil 23 upon the short-circuiting of the coil 22 caused by the short-circuiting of the resistor 6.

It will be noted that, in the systems of Figs. 5 and 8, a triple check against starting 90 the motor in the reverse direction, with the resistance short-circuited is provided, consisting of preventing the motor circuit being completed until the armature 32 has returned to normal position, the provision for 95 reversing the magnetism of the coils 22 and 23 and the provision for reversing the magnetism of the coils 19, 20 and 21 for actuating the resistor-short-circuiting contactors 10, 11 and 12.

In my above mentioned application, it is pointed out that, though I preferred to employ the De Camp relay, the invention is not limited thereto, but may be adapted to control systems embodying the use of ordinary 100 relays. In Fig. 9, I illustrate one method of reversal for such a control system. The relays 25, 26 and 27 are here of the ordinary type, each energized by an individual coil 22^a, 22^b and 22^c. The relay 25 is provided 11 with a switch member 55^a mechanically interlocked therewith, this switch member being open when the relay is closed and closed when the relay 25 is open.

The reversing contactors, of the interlocked type shown in Figs. 6, 7 and 8, are each provided with a pair of mechanically interlocked contactors 67 and 88, and 66 and 90, the contactors 67 and 66 being open and the contactors 88 and 90 being closed when 120 the reversing contactors are open, and vice versa. A line contactor 5 is employed, as in the systems of Figs. 6 and 8. The con-

troller 7 is of the form illustrated in Fig. 8, though any equivalent form may be employed.

The function of the various additional switches and contactors above referred to will be explained in connection with the description of the operation which is as follows: Assuming that the controller 7 has been moved to the left, a circuit is established which extends from the line conductor 3, through the controller 7, the contact member 9^b and the actuating coil 8 of the line contactor 5, to the line conductor 4. The line contactor 5 is thereupon closed. This action causes the closing of the circuit extending from the line conductor 3, through the conductor 85, the contactors 90 and 88, which occupy their closed positions when the reversing contactors are open, a resistor 91, the actuating coils 22^a, 22^b and 22^c, either in series or in parallel, as desired (the parallel relation is here disclosed), and the contactor 5 to the line conductor 4.

The relays 25, 26 and 27 are thereupon immediately opened. The opening of the relay 25 causes the closing of the switch 55^a, whereupon a circuit is established from the line conductor 3, through the controller 7, the contact member 9^a, the actuating coil 63, the switch 55^a and the line contactor 5, to the line conductor 4. The reversing contactors 59 and 60 are thereupon closed, which instantly causes the opening of the contactor 88 to break the circuit of the coils 22^a, 22^b and 22^c. The relays 25, 26 and 27, however, will remain open, due to the fact that a new circuit is created for the coils 22^a, 22^b and 22^c, in parallel with the resistor 6, which is now traversed by current through the motor circuit as follows: from the line conductor 3, through the reversing contactor 59, the armature 1, the reversing contactor 60, the resistor 6 and the line contactor 5, to the line conductor 4.

The circuit in parallel with the resistor 6 for the coils 22^a, 22^b and 22^c includes a resistor 92. As the motor accelerates and its counter-electromotive force increases, the voltage across the terminals of the resistor 6 is decreased, whereupon the relays 25, 26 and 27, which are of different weights, or controlled by springs of different strengths, are successively closed to cause the closing of the contactors 10, 11 and 12 to short-circuit the resistor in a manner that will be well understood from the previous descriptions. The circuits of the actuating coils 19, 20 and 21 may be controlled in the second position of the controller 7. The contactor 67 creates a holding circuit for the coil 63 so as not to deenergize this coil upon the closing of the relay 25 and the consequent opening of the switch 55^a.

To reverse the motor, the controller is actuated to the right. The motor cannot be

restarted in the reverse direction until the reversing contactors both occupy their open positions, as illustrated, because a circuit for the actuating coils 22^a, 22^b and 22^c must be made through the contactors 88 and 90, 70 as above described, and, furthermore, the circuit of the actuating coil 62 of the reversing contactors 58 and 61 cannot be made until the coils 22^a, 22^b and 22^c have been energized, the coil 22^c causing the closing of 75 the switch 55^a to establish the circuit of the coil 62. Provision is thus made for preventing restarting the motor until proper conditions obtain.

A study of the system of Fig. 9 will show 80 that the switch 55^a performs the function of the contact members 55, 56 and 57 of Figs. 5, 6 and 8. In the systems of these figures, it would be possible to substitute for the contact members 55, 56 and 57 corresponding 85 contact members on the armature 33, which would control the closing of the preliminary circuits when the armature 33 is in the open position. Thus, in the system of Fig. 6, the contact member 55 may be identical with the contact member 45 and the contact members 56 may be placed on the other side of the contact member 48, so that the contact members 45 and 48 would be closed when the contact members 45 and 55 would 90 be open, and vice versa. The projection 54 (Fig. 4) could then be omitted. Such changes are thought to be obvious to those skilled in the art and are within the scope of my invention. Other changes will be 100 manifest to those skilled in the electrical art. My invention, furthermore, may be employed in alternating-current, as well as direct-current systems. I desire, therefore, not to be limited save as is indicated by the 105 appended claims.

I claim as my invention:

1. The combination with an electric circuit and a pair of reversing switches therefor, of actuating coils for said switches, 110 means for energizing one of said coils to cause the closing of the corresponding switch and means for preventing the energization of said other coil for a predetermined length of time after the deenergization of said first coil to prevent the closing of said other switch, said means comprising an electro-responsive device, the residual magnetism of which delays its response.

2. In a reversing system for electric motors, the combination with an armature, a resistor in circuit therewith, a plurality of switches for short-circuiting said resistor and a relay for each of said switches, of means for maintaining said relays open under predetermined conditions and means for preventing the reversal of said motor when said maintaining means is operative.

3. In a reversing system for electric motors, the combination with an armature, a 130

- resistor in circuit therewith, a plurality of switches for short-circuiting said resistor and a relay for each of said switches, of means for maintaining said relays open under predetermined conditions, means for overcoming the operative force of said maintaining means, and means for preventing the reversal of said motor when the second-named means is inoperative.
10. The combination with an electric circuit and a controlling switch therefor, of a switch for shunting a portion of said circuit, means for preventing the closing of said shunting switch, means for rendering said preventing means inoperative, and means dependent upon said last named means for governing the closing of said controlling switch.
5. The combination with an electric motor having an armature, a resistor in circuit therewith, a pair of reversing switches, a plurality of switches for short-circuiting said resistor and a relay for each of said switches, of means for preventing the operation of said motor in the reverse direction with said resistor initially short-circuited upon the opening of one of said reversing switches and the closing of another of said reversing switches.
20. The combination with an electric motor having an armature, a resistor in circuit therewith, and a switch for controlling the circuit of said motor, of a coil in shunt relation to said resistor, a pair of armatures controlled by said coil, means for preventing the closing of one of said armatures until after the closing of said other armature, a switch controlled by said one armature for short-circuiting said resistor, and means controlled by said other armature for controlling the closing of said switch.
25. The combination with an electric motor having an armature, a resistor in circuit therewith, of a coil in shunt relation to said resistor, a switch controlled by said coil for short-circuiting said resistor and said coil, a second coil controlled by said switch for controlling said armature after said first coil is short-circuited and means for causing said coils to
30. The combination with an electric motor having an armature, a resistor in circuit therewith, and a switch for controlling the circuit of said motor, of a coil in shunt relation to said resistor, a pair of armatures controlled by said coil, means for preventing the closing of one of said armatures until after the closing of said other armature, a switch controlled by said one armature for short-circuiting said resistor, and means controlled by said other armature for controlling the closing of said switch.
35. The combination with an electric motor having an armature, a resistor in circuit therewith, of a coil in shunt relation to said resistor, a switch controlled by said coil for short-circuiting said resistor and said coil, a second coil controlled by said switch for controlling said armature after said first coil is short-circuited and means for causing said coils to
40. The combination with an electric motor having an armature, a resistor in circuit therewith, and a switch for controlling the circuit of said motor, of a coil in shunt relation to said resistor, a pair of armatures controlled by said coil, means for preventing the closing of one of said armatures until after the closing of said other armature, a switch controlled by said one armature for short-circuiting said resistor, and means controlled by said other armature for controlling the closing of said switch.
45. The combination with an electric motor having an armature, a resistor in circuit therewith, of a coil in shunt relation to said resistor, a switch controlled by said coil for short-circuiting said resistor and said coil, a second coil controlled by said switch for controlling said armature after said first coil is short-circuited and means for causing said coils to
50. The combination with an electric motor having an armature, a resistor in circuit therewith, and a switch for controlling the circuit of said motor, of a coil in shunt relation to said resistor, a pair of armatures controlled by said coil, means for preventing the closing of one of said armatures until after the closing of said other armature, a switch controlled by said one armature for short-circuiting said resistor, and means controlled by said other armature for controlling the closing of said switch.
55. The combination with an electric motor having an armature, a resistor in circuit therewith, and a switch for controlling the circuit of said motor, of a coil in shunt relation to said resistor, a switch controlled by said coil for short-circuiting said resistor and said coil, a second coil controlled by said switch for controlling said armature after said first coil is short-circuited and means for causing said coils to
60. The combination with an electric motor having an armature, a resistor in circuit therewith, and a switch for controlling the circuit of said motor, of a coil in shunt relation to said resistor, a pair of armatures controlled by said coil, means for preventing the closing of one of said armatures until after the closing of said other armature, a switch controlled by said one armature for short-circuiting said resistor, and means controlled by said other armature for controlling the closing of said switch.
65. The combination with an electric motor, a resistor in circuit therewith, of means for short-circuiting said resistor, a coil, means controlled by said coil for establishing the circuit of said motor, means for thereupon deenergizing said coil, a second coil for effecting the short-circuiting of said resistor, said second coil being thereupon deenergized, and means for reinserting said first coil into circuit to maintain said resistor short-circuited.
70. The combination with an electric motor, a resistor, and a coil in parallel therewith, of an armature controlled by said coil, a switch controlled by said armature for closing the circuit of said motor, a switch controlled by said armature for short-circuiting said resistor and a second coil controlled by the second switch for controlling said armature after said resistor is short-circuited.
75. The combination with an electric motor, a resistor, and a coil in parallel therewith, of an armature controlled by said coil, a switch controlled by said armature for short-circuiting said resistor and a second coil controlled by the second switch for controlling said armature after said resistor is short-circuited.
80. The combination with an electric motor having an armature and a resistor in circuit therewith, of a coil in shunt relation to said resistor, a switch controlled by said coil for short-circuiting said resistor and means controlled by the other armature for short-circuiting said translating device.
85. The combination with an electric motor having an armature and a resistor in circuit therewith, of a coil in shunt relation to said resistor, a switch controlled by said coil for short-circuiting said resistor and means controlled by the other armature for short-circuiting said translating device.
90. The combination with an electric motor having an armature and a resistor in circuit therewith, of a coil in shunt relation to said resistor, a switch controlled by said coil for short-circuiting said resistor and means controlled by the other armature for short-circuiting said translating device.
95. The combination with an electric motor having an armature and a resistor in circuit therewith, of a plurality of switches for controlling said resistor, a switch for partly closing the circuit of said motor, means for normally maintaining said last-named switch closed and said first-named switches open, and means for preventing the reversal of said motor until said switches occupy said normal positions.
100. The combination with an electric motor having an armature and a resistor in circuit therewith, of a coil in shunt relation to said resistor for effecting the short-circuiting of said resistor and means for preventing the reversal of said motor until the reversal of the magnetism of said coil.
105. The combination with an electric motor having an armature and a resistor in circuit therewith, of a coil in shunt relation to said resistor for effecting the short-circuiting of said resistor and means for preventing the reversal of said motor until the reversal of the magnetism of said coil.
110. The combination with an electric motor having an armature, a resistor in circuit therewith, and a switch for short-circuiting said resistor, said switch having an actuating coil, of means for starting said motor and means for preventing the short-circuiting of said resistor after the reversal of said motor until after the reversal of the magnetism of said coil.
115. The combination with an electric motor having an armature, a resistor in circuit therewith, and a source of current for said motor, of a switch for closing the circuit of said motor, a plurality of switches for short-circuiting said resistor, a relay for each of said short-circuiting switches, means controlled by the voltage of said resistor for closing said relays, means controlled by the

- voltage of said source for maintaining said relays closed, means for opening said circuit-closing switch before reversing the current in said armature, said voltage-controlled means thereupon becoming inoperative, means for reclosing said circuit-closing switch and means for preventing the simultaneous closing thereupon of said switches for short-circuiting said resistor.
- 10 16. The combination with an electric motor, a resistor, a switch for closing the circuit of said motor and a switch for effecting the short-circuiting of said resistor, of an actuating coil for each of said switches, means for energizing the coil of the second switch when said first switch occupies an operative position, and means for energizing the coil

of the first switch when said second switch occupies an inoperative position.

17. The combination with an electric motor, a resistor and a switch for closing the circuit of said motor, of a switch for effecting the short-circuiting of said resistor and having an actuating coil, means for energizing said coil when the first switch occupies 20 an inoperative position and means for maintaining said coil energized after said first switch has been actuated to an operative position.

In testimony whereof, I have hereunto 30 subscribed my name this 30th day of July, 1918.

HENRY D. JAMES.
